(57) **CLAIM**

The ornamental design for an interchangeable self-locking spring loaded quick connect apparatus for cable, as shown and described.

DESCRIPTION

FIG. 1 is a front, top, right side perspective view of an interchangeable self-locking spring loaded quick connect apparatus for cable embodying our new design;

FIG. 2 is a rear, bottom, right side perspective view of FIG. 1;

FIG. 3 is a front view of FIG. 1;

FIG. 4 is a rear view thereof;

FIG. 5 is a right side view of FIG. 1, the left side view being a mirror image thereof;

FIG. 6 is a top plan view of FIG. 1; and,

FIG. 7 is a bottom plan view of FIG. 1.

1 Claim, 2 Drawing Sheets

FIG. 1

FIG. 2

FIG. 3

FIG. 4

FIG. 5

FIG. 6
